(57) **CLAIM**

The ornamental design for an ultrasonic cutter head as shown and described.

DESCRIPTION

1. Ultrasonic cutter head

Figure 1.1 is a front view of an ultrasonic cutter head;

Figure 1.2 is a back view thereof;

Figure 1.3 is a left side view thereof;

Figure 1.4 is a right side view thereof;

Figure 1.5 is a top view thereof;

Figure 1.6 is a bottom view thereof;

Figure 1.7 is a perspective view thereof;

Figure 1.8 is an enlarged view thereof, taken from the encircled portion labeled as 1.8 in Figure 1.2; and

Figure 1.9 is an enlarged view thereof, taken from the encircled portion labeled as 1.9 in Figure 1.1.

The dash-dot-dash broken lines in Figures 1.1, 1.2, 1.8, and 1.9 are included to show a partially enlarged view only and form no part of the claimed design. The portions shown in broken lines shown in the figures are for the purposes of illustration only and do not form part of the design.
